UNITED STATES PATENT OFFICE

2,476,985

RECEIVER FOR ELECTRICAL PULSES

Maurice Moïse Levy, London, England, assignor,
by mesne assignments, to International Standard
Electric Corporation, New York, N. Y., a
corporation of Delaware

Application January 16, 1945, Serial No. 573,101
In Great Britain December 1, 1943

Section 1, Public Law 690, August 8, 1946
Patent expires December 1, 1963

3 Claims. (Cl. 315—9)

1

The present invention relates to receivers for electrical signals, particularly pulses and which utilise a cathode ray oscilloscope for giving an indication of the reception of the signals which have a tendency to be masked by noise signals.

Receivers of the type specified are particularly applicable, for example, to radio location equipment for determining the presence of objects, for example, such as aircraft, or for determining distance by the utilisation of the reflection of electrical pulses in the form of direct current pulses or in the form of trains of high frequency waves which are detected to produce a direct current pulse which is then applied to the cathode ray oscilloscope to obtain the required indication. The invention is also applicable to other cases utilising the reception of an electromagnetic signal wave which requires a relative indication rather than an absolute value indication. For instance, in some cases utilising the reflection of electromagnetic waves, it is desired to adjust the frequency of the transmitted continuous wave until the wave received, after reflection at an object, has a specific phase relationship, for example, in phase or anti-phase, to the contemporaneously transmitted wave. The frequency of the transmitted wave is adjusted until this condition is attained which condition is given by an indication on the oscilloscope screen.

In obtaining these indications the electron beam is caused to scan the screen in one direction, for example, the horizontal or abscissa direction under the control of a time base circuit whose period is equal to the pulse repetition period or other convenient period. The received signal is applied after the necessary treatment, for example, amplification and rectification, to cause the beam to be deflected in a direction perpendicular to the scanning direction, i. e. the vertical direction in the example given.

These reflected signals, as will be understood by those skilled in the art, are very weak in intensity or energy level, and are difficult to detect when mixed with noise which appears on the oscilloscope screen as an irregular wavy horizontal line which tends to mask the indication of the received signal.

It is the object of this invention to provide arrangements for increasing the signal to noise ratio of the indication on the oscilloscope screen and thus rendering the signal indication more clearly distinguishable and prominent against the background noise effect produced on the screen.

The invention resides in limiting the vertical or ordinate deflection of the electron beam to a predetermined ordinate value irrespective of the instantaneous deflecting force of the received signal above that predetermined ordinate value.

2

Arrangements according to this invention comprise an amplitude limiting device which limits the amplitude of the received signal before application to the ordinate deflecting unit of the cathode ray tube. By this means the deflecting force on the electron beam is maintained substantially constant during the greater period of reception of the signal, with a consequential brighter indication on the screen during that portion of the period compared to the brightness during the remaining portion of the period when the ordinate deflecting force is less than or does not persist for so long as the deflecting force due to the signal above the predetermined value.

15 The invention also includes arrangements for increasing the visibility of indications produced by contrast of the intensity of illumination of an area with respect to the intensity of illumination of surrounding areas comprising means for 20 scanning said areas, for example, a cathode ray oscilloscope screen having an indication produced as hereinbefore specified, as regards intensity of illumination and means for producing an amplified indication of the variation of intensity of 25 light along the direction of scanning.

The principle on which the invention is based is deduced from the law of distribution of the peak amplitudes in the noise.

The invention will be more clearly understood 30 from the following description taken in conjunction with the accompanying drawings in which

Figs. 1a, 1b, 1c, 2a, 2b, 3, 4 and 5 show curves used in explaining the invention;

Fig. 6 shows the circuit arrangements of an 35 embodiment of the invention, given by way of example only;

Fig. 7 is a further explanatory curve;

Fig. 8 shows diagrammatically an arrangement 40 for improving the indication obtained by means of the present invention;

Figs. 9 and 9b show the kind of trace obtained 45 by the improved arrangement shown in Fig. 8; and

Figs. 10 and 11 show, diagrammatically, arrangements according to the invention.

The noise may be looked upon as the resultant 50 of an infinite number of pulses of very short duration, the amplitudes being distributed at random. It will be assumed that these amplitudes follow Gauss' law of distribution. If a curve be traced, the ordinates of which represent the peak amplitudes of the noise pulses and the abscissae the proportion of pulses occurring in a specified time having a given peak amplitude, that is the 55 value of the probability for a noise pulse to have a given amplitude, a curve such as the one represented at C in Fig. 1a is obtained. Pulses having zero amplitude are the most probable and the

probability decreases very quickly when the amplitude increases. If Z is the amplitude of specified noise pulses and p the probability of those pulses, this curve may be represented by the equation

$$p = \frac{k}{\sqrt{\pi}} \theta^{-k^2/2} \quad (1)$$

where k is a constant connected to the root mean square value

 αn

of the noise amplitude by the relation

$$\alpha n = \frac{1}{k \sqrt{2}} \quad (2)$$

Now since the movement of the spot of the cathode ray tube is random the time during which the spot is at a certain amplitude follows the same kind of law, and the distribution of the intensity on the screen produced by the movement of the spot follows also the same law. That is to say, the curve C of Fig. 1a represents also the law of the vertical distribution of the intensity due to noise. This intensity is maximum on the abscissa line and decreases very quickly at points away from it.

It should be observed that this is really a hypothesis exactly as Gauss' law of distribution. This hypothesis is most probably correct. However, even if the intensity distribution follows a different kind of law, the general principles of the method explained hereinafter can still be applied. For simplicity, and as an example, it will be assumed that the conditions obey the laws referred to.

What happens when the signal pulses are mixed with the noise will now be discussed. Fig. 1c represents the resultant of the noise of Fig. 1a and the pulse of Fig. 1b. When a signal pulse appears, its effect is to increase the noise deflecting force by an amount equal to the amplitude of the signal pulse. This has been shown at B in Fig. 1c. The intensity distribution curve has been traced for a point A where there is no signal pulse and for a point B where the signal pulse is present. The intensity distribution law is the same, but the pulse raises the curve by an amount equal to the pulse amplitude.

The value of the minimum amplitude of the signal pulse which can be visible can now be found, that is, the minimum value of the signal noise ratio for which the presence of a signal pulse may be detected by visual observation.

In Fig. 1c the root mean square noise amplitude (standard deviation in statistics) has been represented by the ordinate $A\alpha n$. The intensity of light for this point is nearly 60% of the value for point A. Assuming a variation of 40% is nearly the minimum variation which can be distinguished, one can see that the minimum lift of curve B making this variation In visible is, in the example shown, equal to $A\alpha n$. Thus, the minimum signal/noise ratio for visibility of the signal pulses is approximately one.

A method by which much smaller values of signal/noise ratio can be made visible will now be described.

One practical means is to insert an amplitude limiter in the receiver, at any point before the cathode ray tube.

The effect of this limiter on the intensity distribution on the cathode ray tube will now be examined. Assume first no pulse signal is received. Without the limiter the intensity distribution curve is assumed to be Gauss' curve as

represented at C in Fig. 1c and Fig. 2a. Assume now the limiter cuts all amplitudes above or below a given value, $A\alpha L$ above if $A\alpha L$ is greater than 0 and below is if $A\alpha L$ is less than 0 (Fig. 2a). Then all the intensity of light which was spaced above the horizontal line passing through point αL is concentrated on this line. This is due to the fact that whenever the spot has a tendency to cross this line and trace a curve above it, it is stopped by the limiter and stays on this boundary line during the time which it would otherwise have spent about it, in the absence of the limiter. Thus, the average intensity on this line is equal to the area of the intensity distribution curve occurring above this line. This average intensity is negligible when $A\alpha L$ is great and increases gradually when $A\alpha L$ decreases and becomes sharply maximum when $A\alpha L=0$ (see curve D, Fig. 2a) whereas the amplitude of the noise intensity distribution (curve C) varies very slowly for very small values of $A\alpha L$. If $A\alpha L$ starting from a zero value increases by a very small quantity, the noise intensity light will not vary, but if a limiter is used the variation will be marked (compare curves C and D, Fig. 2a). This property is used in carrying out the present invention in order to increase the visibility of indications due to very small pulses. The principle is to use an amplitude limiter, preferably adjusted so that $A\alpha L$ is small or zero, and to observe on the horizontal scanning line produced by the limiter the difference of intensity between the points or instants where there is only noise and the points where the noise is mixed with a signal pulse. This difference in intensity is explained as follows.

Fig. 2b represents the average intensity light on the scanning line for two points: one A, where there is no signal pulse, and one, B, where the noise is mixed with a signal pulse. The effect of the pulse is to lift the noise curve of a height α equal to the amplitude of the pulse. The average intensity on the scanning line at point A is I_0 , the maximum amplitude of the curve I_b , and at point B it is I_p . The difference $I_0 - I_p$ is proportional to α when α is small because the curve near the cusp is approximately constituted by two straight lines. Without the limiter for very small values of α there is no appreciable variation of intensity along the sweep line, as already explained in connection with Fig. 1c.

To have an idea of the improvement introduced by this method some calculations are necessary.

Let In be the noise light intensity for an ordinate of abscissa Z . The law of distribution of the intensity of light is given by

$$In = \frac{K}{\sqrt{\pi}} \theta^{-K^2 Z^2} \quad (3)$$

where K is a constant connected to the root mean square value of In by the relation

$$\overline{In} = \frac{1}{K \sqrt{2}} \quad (4)$$

Let Ib be the intensity of light on the scanning line $Z-\alpha$, when there is a limiter. Then we have

$$Ib = \int_{\alpha}^{\infty} IndZ = \int_0^{\infty} IndZ - \int_0^{\alpha} IndZ$$

$$Ib = \frac{1}{2} - \frac{K}{\sqrt{\pi}} \int_0^{\alpha} \theta^{-K^2 Z^2} dZ \frac{1}{2} - \frac{1}{\sqrt{\pi}} \int_0^{K\alpha} \theta^{-\theta^2} dt$$

$$2Ib = [1 - \text{(+)}(K\alpha)] \quad (5)$$

where $(+)(K\alpha)$ is the well known integral used in statistics problems. There exists numeri-

cal tables of this integral and from these tables the curve shown in Fig. 3 can be traced. In this figure the curve representing In is also shown and to make comparison easier, the two curves are given the same maximum amplitudes. The root mean square amplitude of the noise is represented by the abscissae αn as in Fig. 1c. The intensity In corresponding to the root mean square amplitude is also represented. It may be seen that with curve Ib the same amplitude In can be obtained with half the deflection αn , that is to say with half the amplitude of the signal pulse which will be necessary with curve In . Thus, the above method improves the signal to noise ratio by about 6 db's.

It may be noticed that the adjustment of the limiter may be independent of the amplitude of the noise and signal pulses and a limiter suppressing either the positive or the negative part of the signals may be used. Any amplitude limiter, for example a biased amplifier, can be used. Many such limiters are well known and practically all are very simple. Thus the invention is very easy to embody, even in any existing cathode ray oscilloscope indicating apparatus.

The above theory is only approximate because of the example of intensity curve chosen. In practice, the scanning line produced by the limiter must be adjusted in order to get the best results.

In the description given hereinbefore, the intensity distribution law has been assumed to be identical to Gauss' law. Experiments have shown that the phenomenon described does occur in practice. It is interesting to notice, however, that this phenomenon is practically independent of the kind of intensity distribution law so long as the law which the intensity distribution does follow presents a slow rate of change of intensity with distance from the sweep line at the point of maximum intensity (curve C, Fig. 2a). That is, the first derivative or tangent at the maximum of curve C is zero, and the curve representing the law is convex at its maximum rather than cusp-shaped like curve D. A complete analysis shows that even if curve C is cusp-shaped, the phenomenon occurs for $AaL=0$ providing that the maximum amplitude of curve C is less than the maximum amplitude of curve D.

The case will now be considered of a limiter whose cut-off amplitude varies progressively from $-\alpha$ to $+\alpha$.

Referring to Fig. 2a, it may be seen that the limiter limits all peaks whose maximum amplitude is greater than AaL : negative peaks are not limited. If AaL has a negative value, the limiter can limit either all peaks above the limiter line (line parallel to the abscissae and whose ordinates are equal to AaL) or below this line. To trace the symmetric Gauss' curve of Fig. 2a, it has been assumed that the peaks below this line are limited. We will examine now the case where all peaks above this line or alternatively all peaks below this line are always limited whatever may be the sign of AaL .

Assume that all peaks below the limiter line are limited. If $AaL=-\alpha$, the intensity along the limiter line is zero. When the limiter amplitude comes nearer zero, the intensity along this line increases following a law represented by Gauss' curve (curve C, Fig. 2a, or curve C, Fig. 4). When the limiter amplitude is positive, the intensity still increases, as we assume that all peaks below this line are limited. Finally, at the limit, when the

limiter amplitude is $+\alpha$, the intensity is maximum. The law is represented by curve C, Fig. 4.

With this kind of limiter, Fig. 2b becomes as represented in Fig. 5 (with the notations of Fig. 2b), except that the limiter as regards Fig. 5 is suppressing the signal above the limiter line instead of below this line as is the case for Fig. 2b. The limiter giving the conditions shown in Fig. 5 may be said to give results which are complementary to those given by the limiter studied in connection with Figs. 2a and 2b.

All these different kinds of limiters are easy to produce by those skilled in the art. A simple circuit is represented in Fig. 6. The noise mixed with signals is applied at P on the input grid G of an amplifying valve V. The plate resistance R is shunted by a diode E in series with a battery F. The plate of valve V is also connected to plate of diode E. The cathode of diode E is connected to battery F. Valve V is preferably a pentode so that plate voltage variations do not affect the plate current of the valve. It is clear that this circuit will act as a limiter of the type described above. If the current of valve V is small and assuming the H. T. voltage is greater than the voltage of the battery F, a current will flow across R and diode E to battery F so that the voltage across diode E is small; let I_s be this current; the voltage across resistance R will start to vary only when the plate current of valve V is greater than I_s . This explains the limiter action of the diode. AaL can be adjusted by a convenient choice of the voltage of battery F.

The potentials across R are applied to the vertical deflecting plates of a cathode ray oscilloscope O and a time base circuit T provides the horizontal deflecting potentials for O.

In order to make the indication obtained on the cathode ray oscilloscope screen more visible, two limiters may be used, for example, two amplifier valves fed in parallel with the signal and noise and each having a limiter connected in its output, for example as shown in Fig. 6. A cathode ray oscilloscope having a double beam, that is, two beams or one split beam is used and one limiter is arranged to suppress the lower part of the signal and noise pattern, so as to produce the trace 1 with one beam as shown in Fig. 7, whilst the other limiter is arranged to suppress the upper part of the pattern and produce a trace as shown in trace 2, Fig. 7, with the other beam as hereinbefore described. Trace 1 is identical to the trace shown in Fig. 2b, and trace 2 is identical with the trace shown in Fig. 5. A pulse is shown as occurring between the times t_1 and t_2 and it will be seen that the intensity of illumination of trace 1 during the pulse is weaker whilst in trace 2 the intensity is stronger. The presence and occurrence of the pulse is seen more clearly by the contrast between the two traces.

Fig. 10 represents, diagrammatically, an arrangement incorporating this feature of the invention.

In another alternative arrangement shown diagrammatically in Figs. 8 and 11 for making the indication of a received pulse more visible, an opaque screen 10 covering the face of the oscilloscope screen 12 is provided with a horizontal slit 11 located so as to expose only the horizontal trace of the oscilloscope. This slit is also covered and means are provided for un-75 covering in a sweeping movement a small area

of the slit. Such means may comprise a further disc 13 having slots 14, the disc 13 being rotated by the motor 21. The disc 13 may be in the form of a Nipkov disc as used to scan a screen in television apparatus or the disc may have a continuous spiral slit in place of the spiral series of holes. By this means only one small or elemental area of the trace of the oscilloscope 15 is visible at a time. The light from this small area is focussed by a lens 16 on to a photoelectric cell 17. The horizontal plates of the oscilloscope 18 are connected to a time base 22 synchronized with disc 13, for example, by a mechanical liaison with motor 20, as shown in the drawing. If the sweeping frequency of this small or elemental area is small compared to the sweeping frequency of the beam of the oscilloscope 15, the photoelectric cell current will be proportional to the average intensity of the moving elemental area over the trace. This current may then be used to produce the trace of a cathode ray beam of a second oscilloscope 18 after suitable amplification in an amplifier 19, or to operate a mechanical indicator. In the case of the second oscilloscope, the trace 20 will represent the average intensity distribution of light along the trace on the first oscilloscope screen and will appear as shown in Fig. 9a in the case of an original trace such as 1 in Fig. 7 in which a pulse is indicated by a reduction of the intensity or as in Fig. 9b in the case of an original trace such as 2 in Fig. 7 in which a pulse is indicated by an increase in the intensity.

It will be understood that the arrangements described for increasing the visibility of a pulse indication are not limited in their application to a system of the kind described in relation to Figs. 1 to 5, but are of general application for increasing the visibility of indications produced by contrast of the intensity of an area with respect to the intensity of illumination of surrounding areas.

What is claimed is:

1. Arrangements as claimed in claim 3 comprising means for scanning the trace produced on the oscilloscope screen and means for producing an electric current which varies in accordance with the intensity of light along said trace,

a second cathode ray oscilloscope whose beam is deflected in one direction in synchronism with the scanning of said trace, and in the other direction by said current.

5 2. Arrangements as claimed in claim 3 comprising means for successively and cyclically exposing elemental areas of the oscilloscope trace, a photo-electric cell, means for focussing the light from said elemental areas on to said cell to produce a current which varies in accordance with the intensity of light in the successive elemental areas exposed, an amplifier for amplifying said current or voltage derived therefrom and a second cathode ray oscilloscope whose beam is cyclically deflected in one direction in synchronism with the cyclic exposing of the trace, and in a perpendicular direction by the amplified currents or voltages derived therefrom.

20 3. A signal indicating system particularly for signals whose amplitudes are small compared to the noise amplitude comprising means for limiting the amplitudes of said signals in the presence of noise and means to apply clipped signals to an oscilloscope whereby the signals appear on the 25 oscilloscope trace in the form of sections of weaker or stronger illumination, means for scanning said oscilloscopic trace sections and means responsive to said scanning means and including a second oscilloscope for indicating said weaker or stronger illumination.
